LESTER A. WERNERY, OF BROOKLYN, NEW YORK, ASSIGNOR TO UNDERWOOD TYPE WRITER COMPANY, OF NEW YORK, N. Y., A CORPORATION OF DELAWARE.

TYPE-WRITING MACHINE.

1,214,733.

Specification of Letters Patent.

Patented Feb. 6, 1917.

Application filed June 21, 1915. Serial No. 35,211.

To all whom it may concern:

Be it known that I, LESTER A. WERNERY, a citizen of the United States, residing in Brooklyn-borough, in the county of Kings, 5 city and State of New York, have invented certain new and useful Improvements in Type-Writing Machines, of which the following is a specification.

The present invention relates to means in 10 a typewriting machine for holding and guiding cards and the like as the same are fed into the machine, inscribed and ejected therefrom.

Owing to the small size of certain cards, 15 such for instance as address cards and library cards, and to the comparative stiffness of the material of which they are composed, it is now common to provide some special means for holding and guiding them 20 in a typewriting machine. Such special mechanism is preferably attachable to the machine and removable therefrom, being used only when cards are to be written. Facility of removal and attachment with 25 a minimum of interference with other parts of the machine is therefore a desideratum in mechanism of this character.

It is an object of the present invention to have the card-holding and guiding mechanism of such compact and simple structure 30 that as a unit it may be attached to and removed from a standard typewriting machine, without necessitating any material change in the other parts of the machine. 35 To use the present invention in connection with an Underwood machine, for instance, it is only necessary to remove the front feed rolls of the same; and any operator can thus readily convert his machine into an address- 40 ing machine.

It is an object of the invention to so construct the card-holding and guiding mechanism that injurious bending of the cards is obviated; and it is a further object of the 45 invention to automatically, as the cards are ejected, correct and eliminate any bending of the cards which may have taken place during the introduction and printing of the same. To these ends, there is provided a 50 special support for the part of the card beyond the printing line, so that the card will not have to be turned closely around the platen in order to be properly supported. At the printing line the card is supported 55 against the platen preferably by a set of feed

rollers which form part of the removable attachment. For eliminating any curvature the cards may have received in the printing operation, there is provided as part of the invention a card-deflecting device, preferably a plate, against which in the card-ejecting movement of the platen, the card is forced and bent in a direction opposite to that of the curve of the platen; this reverse bending being just sufficient to straighten 60 out the card.

Another object of the invention is to have the card guides and feed rollers adjustable independently of the card holder or support, so that without change in the latter, the 70 mechanism may be adjusted to various sizes of cards, any of which will be accommodated by the holder. Preferably one of the feed rollers is mounted on each lateral guide, and the two latter are independently movable longitudinally of the platen frame. It is also an object of the invention to provide means for adjusting the pressure of the feed rollers on the cards, and to this end the feed 75 roller supports are preferably held against 80 the cards by springs, the tension of which may be varied in any suitable manner.

To permit of ready insertion of the cards, it is an object of the invention to provide for removal, at will, of the feed rollers, from the 85 platen; and, if the feed rollers are mounted in the guides, to provide for slight movement of the latter perpendicularly to the axis of the platen, without however impairing their 90 function as guides for the cards as the latter are inserted.

An object of the invention is a mechanism of the general character described, which, in its use does not involve the removal of the 95 ribbon from the machine, but which, on the contrary, may be used or not used, in conjunction with the ribbon, so that either writing or stenciling may be made upon the card, or both writing and stenciling upon the same card.

Still another object of the invention is to provide an adjustable stop against which the cards are fed to determine and vary the location on the card of the line first to be written thereon.

Other features and advantages will hereinafter appear.

In the accompanying drawings, Figure 1 is a view in perspective of the card holder and associated parts, assembled, and in oper- 110

ative position, on the platen frame of an Underwood typewriter. Fig. 2 is a view in cross sectional elevation, taken on the line 2—2 of Fig. 1, a card being shown in position for printing, and a type being shown at the printing point. Fig. 3 is a view similar to that of Fig. 2, except that no card is shown in the holder, and that the card feed-roller appears in normal position. Fig. 4 is a view similar to that of Fig. 3, except that the card feed-roller is shown as held away from the platen, by depression of the finger-piece which controls it, while a card is being positioned in the holder.

Referring to the drawings, which show the invention as applied to an Underwood typewriting machine, the platen frame 1 carries the usual paper shelf 2, and platen 3; the platen being carried on the shaft 4 which is revolubly mounted in the platen frame. The platen may be rotated by the hand wheels 5, fast to the ends of the platen shaft; or may receive a definite line-space feed by means of the ratchet wheel 6, which is fast to the shaft, and which is adapted to be turned in the usual manner by a pawl (not shown). The pawl is carried by a spring-controlled slide 8 on the platen frame, in turn operated from the bell-crank 9, which is pivoted to the machine frame at 10, and which carries a suitable line-space finger piece 11. The platen frame 1 has its letter-feed movement in the usual manner on a rail 12 mounted in the frame 13 of the machine.

The ribbon-carrying and vibrating mechanism shown in the drawings, is that of an Underwood typewriting machine; the ribbon being shown at 14 in the carrier or vibrator 15, which in the ordinary printing operation, throws it, at each type stroke, from a position below the printing point, to the printing point, whence it drops again to its position below the printing point. This vibration of the ribbon-carrier is effected from a universal bar, not shown, but which is common to Underwood typewriting machines, and which has a back and forth movement at each type stroke to provide a letter-feed movement of the carriage. For vibrating the ribbon-carrier from the universal bar, the latter carries a slotted bracket 16. In the drawings, this bracket is shown as having two slotted ears 17 and 18, because the ribbon therein shown is a bi-chrome ribbon having a black upper band 19 and a red lower band 20; and therefore, according to which band is to be presented to the printing point, requires a greater or lesser throw of the vibrator. The vibrator lever 21 is a two-armed lever pivoted at 22, one arm 23 of which connects with the vibrator, and the other arm 24 of which carries two pins 25 and 26, one on each side thereof. The arm 24 with its pins 25 and

26 lies between the ears 17 and 18. The ears 17 and 18 on the universal bar are sufficiently far apart to permit of a position in which neither pin 25 or 26 can be engaged by either one of them. The bracket 16 is however shiftable on the universal bar so that ear 17 by means of its slot 27, may interlock with pin 25, or ear 18, by means of slot 28, with pin 26. To slide or shift the bracket 16 on the universal bar, there is connected thereto a rod 29, in turn connected to an arm 30, fast to a rock shaft 31, the forward end of which carries a key lever 32 having a black ribbon key 33 on one side of the shaft 31, and a red ribbon key 34 on the other side of that shaft. Depression of one or the other of these keys locks the universal bar to the vibrator, and, by reason of the different positions of the pins 25 and 26 on the vibrator lever, causes one or the other of the color bands of the ribbon to be presented at the printing point. When the keys 33 and 34 are in neutral or ineffective position, in which they may be locked by a finger lever 36 having a notch 37, to engage a pin 38 on the key lever 32, both ears 17 and 18 are free to be vibrated by the universal bar without moving the ribbon vibrator. This neutral position is that desired in stenciling, and therefore in stenciling, the ribbon 95 remains, as shown in Fig. 1, below the printing point.

The card holder of the present invention is preferably removable from and attachable at will to the machine, and is particularly designed for the writing, or stenciling of cards or similar devices. It is carried on a bar 40, the ends of which are removably secured, by means of screws 41, to the end-pieces of the platen frame. The holder, shown as a pocket 42, is preferably formed of a piece of sheet metal which depends by means of two strips or supporting arms 43 from the bar 40. Screws 44 secure the holder to the bar 40. In one piece with, or suitably secured to, the depending arms 43 is a plate 45, which is first continued downward, as at 46, to form the rear wall of the pocket, or holder, and then at its lower extremity at 47, is abruptly folded over and brought up to form the front wall 48 of the holder. The blank from which the front part 48 is formed may be of sufficient width to permit the ends thereof to be turned over, as at 49, to form end walls for the holder. The arms 43 are curved around the platen, as shown in Fig. 1, to support the upper edge 50 of the back of the holder at a point below and somewhat to the rear of the printing point, ample clearance 51 being allowed between the holder and the platen; and the edge 50 being tapered at 52, so that there is no possibility of the card being caught on the back of the holder.

For properly guiding the card to the

be made upon the frame. Upon insertion of a strip 73 into the pocket, however, the same card would be arrested in a position for stenciling on the material within the frame.

It is to be noted that provided the pockets, or holders, whatever their form, are wide enough, there may be considerable adjustment of the guides 53 longitudinally of the 10 platen to accommodate the mechanism to cards of different sizes.

It is also to be noted that the movement of the feed rollers to and from the platen in inserting the cards involves no disturbance of the holder or pocket, and that the 15 guides 53 are effective whatever the position of the feed rollers.

All parts of the card-guiding and holding device, in the embodiment of the invention 20 hereinbefore described, are removable from and attachable as a unit to the machine.

Variations may be resorted to within the scope of the invention, and portions of the 25 improvements may be used without others.

Having thus described my invention, I claim:

1. In a typewriting machine, the combination with a platen, of guides between which 30 cards may be fed across the printing line, said guides arranged to engage the edges of the cards and control their position lengthwise of the platen, rollers carried by said guides for holding the cards against the platen at the printing line, means to move 35 said guides to carry the rollers away from the platen, and means for varying the pressure of the rollers on the cards.

2. In a typewriting machine, the combination with a platen, of guides having guiding surfaces arranged to engage the edges of cards and between which the cards may be fed across the printing line, and rollers, carried by the guides, for holding the cards against the platen at the printing line, 40 said guides being mounted for movement perpendicularly to the platen axis so that the pressure of the rollers on the cards may be relieved or intensified.

3. In a typewriting machine, the combination with a platen, of edge guides for cards 45 on the platen, rollers for holding the cards against the platen at the printing line, the rollers being mounted on said guides, and means for shifting the guides and thereby 50 lifting the rollers from the platen to permit the insertion of a card.

4. In a typewriting machine, the combination with a platen, of edge guides for cards 55 on the platen, rollers for holding the cards against the platen at the printing line, the rollers being mounted on said guides, means for shifting the guides and thereby 60 lifting the rollers from the platen to permit the insertion of a card, and means for locking 65 the rollers in said lifted position.

5. In a typewriting machine, the combination with a platen frame and platen, of a support mounted on the platen frame ends and extending along the platen above the printing line, rollers bearing against the 70 platen at the printing line, rock arms depending from said support and on which the rollers are carried, brackets on said support, springs connecting the roller arms to the brackets, and cams between the brackets 75 and roller arms for throwing the rollers from the platen against the action of the springs.

6. In a typewriting machine, the combination with a platen, of guides for the edges 80 of cards and by which the position of the cards lengthwise of the platen is controlled as they are fed across the printing line, rollers carried by said guides for holding the cards against the platen at the printing line, 85 means to move the guides in a direction to carry the rollers away from the platen, and means independent of the platen for supporting the card beyond the printing line during the printing operation. 90

7. In a typewriting machine, the combination with a platen, of guides for the edges 95 of cards and by which the position of the cards lengthwise of the platen is controlled as they are fed across the printing line, rollers carried by said guides for holding the cards against the platen at the printing line, means to move the guides in a direction to carry the rollers away from the platen, an auxiliary support for a part of the card 100 beyond the printing line, and means cooperating with the rollers to hold the card firmly against the platen and auxiliary support during the printing operation. 105

8. In a typewriting machine, the combination with a platen, of guides between which 110 cards may be fed across the printing line, rollers carried by the guides for holding the cards against the platen at the printing line, blades also carried by the guides for holding the card at a part thereof beyond the printing line during the printing operation, and means to swing said guides to carry the rollers and blades toward and from the platen. 115

9. In a typewriting machine, the combination with a platen, of a card support for guiding cards into and out of the machine, and across the printing line, on a curve of radius appreciably greater than that of the platen, whereby injurious bending of the card is avoided, and means for holding the card against said support during the printing operation, said holding means shiftable 120 away from its holding position to permit the cards to move freely to printing position. 125

10. In a typewriting machine, the combination with a roller platen, of means for feeding cards in a bent or curved path across the printing line, and means for automati- 130

holder and for carrying a pair of feed rollers for the card, there are two arms 53, pivotally mounted on the bar 40. Hubs 54, fitted within U-shaped extensions or ears 55 on the arms 53, and secured by set screws 56 to the bar 40, serve to hold the arms or guides 53 against longitudinal movement. The guides 53 also serve to maintain the cards in proper alignment and position when the latter are being written upon, or fed, in the printing operation. They are therefore preferably spaced just far enough apart to permit of easy movement of the cards between them. In order that cards of various sizes may be used, the guides 53 may be set at different distances apart by means of the set screws 56. The pocket 42, if closed at its ends, should be wide enough to accommodate the widest card which may be used. So that the cards in being fed to the pocket may not pass over the front upper edge 57 thereof, the guides 53 preferably have retaining blades 58 attached thereto, which extend into the upper part of the pocket. These are secured in any desired angular position by means of screws 59 which also hold the feed rollers 60.

The feed rollers 60 are normally held against the platen, or against any inserted card (see Fig. 3), by means of two springs 61. These springs at one end engage the threads of screws 62 on plates 63 integral with the hubs 54, and at their other ends are attached to arms 64 which form bell-crank with feed roller-supporting arms 53. By turning the screws 62, the tension of the springs 61 may be adjusted at will. As shown in Fig. 4, the feed rollers may be moved away from the platen against the tension of the springs 61, to permit easy insertion of the card. For effecting this movement, there is mounted in the plates 63 a rock shaft 65, carrying at one end a finger lever 66. The shaft 65 is grooved at 67 (see Fig. 4) in registration with each of the bell-crank arms 64, so that, in the normal position of the shaft 65 (see Figs. 2 and 3) the springs 61 hold the arms 64 within and against the bottom of the grooves 67, thus determining the card feeding position of the rollers. Depression of the finger lever 66, however, causes the shaft 65 to be rocked to Fig. 4 position; and in this rocking movement, the bottoms of the grooves 67 act as cams to force down the arms 64 against the tension of the springs 61, causing the feed rollers to be lifted from the platen. The cams may be extended beyond the grooves 67 in the form of lugs 68 attached to the shaft, which have flattened surfaces 69 to hold the parts in card-inserting position.

It will be noted that when the parts are in Fig. 4, or card-inserting position, the blades 58 lie against the inner forward edge of the pocket, preventing the card from pass-

ing over and outside of the pocket. When, however, the finger piece 66 is in normal position, so that printing or stenciling may be effected by a type bar 75, the blades 58 (see Fig. 2) press the card against the back 70 wall 46 of the holder, which in conjunction with the platen at this time, provides a firm support for the card, without necessitating an injurious bending of the card around the platen below the printing line. 75

A card, or other heavy writing material, tends to retain the curl received by it in being passed around the platen; and, as this curl is objectionable, there is in the present invention, a vertically depending plate 70 80 attached to the bar 40 against which the card strikes on being thrown out of the machine by forward rotation of the platen. This plate turns the card upward, and in so doing, automatically straightens the card before it is finally ejected. 85

The present invention is well adapted for the stenciling of address cards for use in an addressing machine. These cards usually consist of a stencil 71 mounted in a pasteboard or similar frame 72. A comparatively heavy frame will not be injured by the mechanism hereinbefore described, because the card will not be subjected to any excessive bending such as might occur were the 95 card bent closely around the platen. 90

When stenciling the address upon the card, the ribbon keys are in neutral position so that the ribbon is not vibrated upon type strokes, but remains idle, as shown in Fig. 1, below the printing point. It is often however, desired to use the ribbon for making an inscription of some sort upon the card frame, in which event the ribbon keys are unlocked, and one or the other of them is depressed to 105 connect the universal bar to the ribbon vibrator; the card, of course, being positioned to present the proper part thereof to the printing line. 100

One of the important functions of the 110 card holder is that of a stop or gage, whereby the mere insertion of a card causes the same to be set for an inscription at any selected location thereon. To make an inscription through the ribbon upon the upper 115 edge of the stencil frame, the card is therefore set differently than when an inscription is to be stenciled thereon. These different settings are automatically and correctly obtained in the present invention by 120 means of interponents in the form of strips 73 which may be said to constitute false bottoms to the pocket 42. The strips 73 may be inserted into the pocket or removed therefrom through an opening 74 in the end of 125 the pocket. Assuming the pocket to be of the proper depth, the card, on striking the actual bottom thereof, will present the upper edge of its frame to the printing point, and an inscription through the ribbon may 130

- 5   11. In a typewriting machine, the combination with a roller platen, of means for feeding cards in a curved path across the printing line, and a card-deflecting plate arranged to automatically bend the cards a sufficient amount in the reverse direction as the same are ejected from the machine, to make them substantially flat. 10
- 10   12. In a typewriting machine, the combination with a roller platen, of means for feeding cards in a curved path across the printing line, and means for automatically straightening the cards as the same are ejected from the machine by movement of the roller platen. 15
- 15   13. In a typewriting machine, the combination with a roller platen, of means for feeding cards in a curved path across the printing line, and a plate directed toward a point of the platen which is behind the card when the latter is at printing position, said plate so positioned that on movement of the platen, in ejecting the card, the card is driven against the plate and by the latter is deflected in a direction to thereby automatically straighten the card. 20
- 20   14. In a typewriting machine, the combination of a platen, means for guiding a card into position for printing, said means including a card-holding pocket below the printing line on the platen, and having front and rear guiding walls between which the card is guided, and end walls by which the position of the card lengthwise of the platen may be controlled, a stop for determining the position of the first line of printing on a card placed in said pocket, and means for adjusting said stop to vary the location of said first printing line position. 25
- 25   15. In a typewriting machine, the combination with a platen, of a card-holding and guiding device comprising a card-pocket supported below the printing line to receive the lower portion of a card held in printing position at the platen, said pocket comprising front and rear guide walls for the cards and end walls by which the position of the cards lengthwise of the platen may be controlled, and means for varying the position at which the card is held for the first line of writing, said means comprising a strip adapted to be set in said pocket at will to lift the base thereof and thereby vary the location of the first line of writing on the card. 30
- 30   16. In a typewriting machine, the combination with a platen, of a card-holder extending below the printing line on the platen and out of which the card is fed line by line during the printing operation, said holder having a wall extending upwardly from the bottom of the holder with its upper edge close to the printing line, which wall, in conjunction with the platen, forms a back support for substantially the entire surface of the card below the printing line while the card is being written upon. 35
- 35   17. In a typewriting machine, the combination with a platen, of a card-holder extending below the printing line on the platen and out of which the card is fed line by line during the printing operation, said holder having a wall extending upwardly from the bottom of the holder with its upper edge close to the printing line, which wall, in conjunction with the platen, forms a back support for substantially the entire surface of the card below the printing line, while the card is being written upon, and means for holding the card against said supporting wall. 40
- 40   18. In a typewriting machine, the combination with a platen, of a card-holder extending below the printing line on the platen and out of which the card is fed line by line during the printing operation, said holder having a wall extending upwardly from the bottom of the holder with its upper edge close to the printing line, which wall, in conjunction with the platen, forms a back support for substantially the entire surface of the card below the printing line while the card is being written upon, and a device movable after the card is in the holder to force the card against said supporting wall. 45
- 45   19. In a typewriting machine, the combination with a platen, of a card holder out of which the card is fed line by line during the printing operation, said holder having a wall, which, in conjunction with the platen, serves as a back support for the card while the latter is being written upon, and a device movable after the card is in the holder to force the card against said supporting wall, and movable to the opposite wall of the holder to serve as a guide for cards to 50
- 50   the holder. 55
- 55   20. In a typewriting machine, the combination with a platen, of a ribbon vibrator for vibrating a ribbon over the printing point at the type strokes, means for rendering the ribbon vibrator inactive at the type strokes, a card-holding device comprising a pocket located below the printing line between the platen and the ribbon vibrator and having front and rear walls between which the card is guided to printing position, and end walls by which the position of the card lengthwise of the platen may be controlled, said card-holding device comprising a stop for the bottom edge of the card, and means for changing the stop position to present a different part of the card to the printing point for stenciling when the ribbon is inactive. 60
- 60   21. In a typewriting machine, the combi- 65

- 6
nation with a platen and platen frame, of a card holder supported on the frame opposite the platen, card guides to the holder independently supported on the frame and arranged to guide the lateral edges of the cards, card-feeding means carried by said guides and arranged to bear against the face of a card and hold it against the platen, and means to swing said guides to move said feeding means away from the platen.
- 10 22. In a typewriting machine, the combination with a platen and platen frame, of a card holder supported opposite the platen, guides for the cards to the holder adjustable longitudinally independently of the holder to accommodate cards of different sizes and arranged to guide the lateral edges of the cards, card-feeding means carried by said guides and arranged to bear against the face of a card and hold it against the platen, and means to swing said guides to move said feeding means away from the platen.
- 15 23. In a typewriting machine, the combination with a platen and platen frame, of a card holder supported opposite the platen, guides for the cards to the holder adjustable longitudinally independently of the holder to accommodate cards of different sizes, said guides arranged to engage the lateral edges 25 of the cards to guide them, said guides carrying rollers for feeding the cards to and from the holder, and means to swing the guides to move the rollers away from the platen, said guides remaining operative to 30 guide the cards to the holder while said rollers are away from the platen.
- 20 24. The combination with a rotatable platen, of means for supporting a ribbon in front of the platen, a relatively flat card-holder in front of, and extended below the platen, front-strike type-bars, ribbon-vibrating mechanism behind the card-holder operated by the type-bars, and a ribbon-vibrating lever connected to said mechanism and 35 extended below the card-holder to engage the ribbon support in front of the card-holder.
- 25 25. In a typewriting machine, the combination with a roller platen and a ribbon vibrator located in front of the platen and arranged to vibrate up and down over the printing point, of a stationary card-holder extending below the printing line between the platen and the ribbon vibrator and inclined downwardly and rearwardly in a position to prevent interference between said holder and the ribbon vibrator.
- 30 26. In a typewriting machine, the combination with a roller platen and a ribbon vibrator located in front of the platen and arranged to vibrate up and down over the printing point, of a card-holding device detachably mounted on the platen frame and comprising a supporting bar above the platen and arms depending therefrom in front of the platen, and a card-holding pocket carried by said arms below the printing line and interposed between the ribbon vibrator and the platen, said pocket being curved or inclined downwardly and rearwardly from the printing line.
- 35 27. In a typewriting machine, the combination with a rotary platen, of a ribbon vibrator arranged to vibrate up and down in front of the printing line on the platen, a card-holder in front of the platen below the printing-line, actuating mechanism for the vibrator behind the card-holder, and a ribbon-vibrating lever connected to said actuating mechanism and extending forward beneath the card-holder and attached at its forward end to said vibrator for actuating the latter.
- 40 28. In a typewriting machine, the combination with a rotary platen, of a vertically-disposed ribbon vibrator arranged to vibrate a ribbon up and down over the printing line on the platen, and a card-holder comprising a guiding plate located below the printing line between the ribbon vibrator and the platen, said plate being inclined downwardly and rearwardly to hold the card deflected or curved inwardly to bear against the platen at the printing line, said inclined position of the plate also preventing interference between the ribbon vibrator and said plate.
- 45 29. In a typewriting machine, the combination with a rotary platen, of a vertically-disposed ribbon vibrator arranged to vibrate a ribbon up and down over the printing line on the platen, a card-holder comprising a guiding plate located below the printing line between the ribbon vibrator and the platen, said plate being inclined downwardly and rearwardly to hold the card deflected or curved inwardly to bear against the platen at the printing line, said inclined position of the plate also preventing interference between the ribbon vibrator and said plate, feed rolls carried by said holder and arranged to bear against a card at the printing line and cause said card to be fed upwardly as the platen is rotated in a forward direction, and a deflecting plate above the printing line to deflect the card outwardly above the printing line, so that the card will be flattened as it is fed upwardly.
- 50 30. In a typewriting machine, the combination with a roller platen, of a ribbon vibrator arranged to vibrate the ribbon up and down over the printing line on the platen, and a stationary card-holder comprising a pocket extending downwardly below the printing line between the vibrator and the platen and curved or inclined inwardly, said inclination or curvature being such that a card held by the holder is curved over the platen but with the radius of curvature substantially greater

- than that of the platen surface, whereby a stiff card may be held closely against the platen at the printing line without being bent to an objectionable extent, said position and form of the card-holder also avoiding interference with the ribbon vibrator.
31. In a typewriting machine, the combination with a roller platen, of a ribbon vibrator arranged to vibrate the ribbon up and down over the printing line on the platen, and a stationary card-holder comprising a pocket extending downwardly below the printing line between the vibrator and the platen and curved or inclined inwardly, said inclination or curvature being such that a card held by the holder is curved over the platen but with the radius of curvature substantially greater than that of the platen surface, whereby a stiff card may be held closely against the platen at the printing line without being bent to an objectionable extent, said position and form of the card-holder also avoiding interference with the ribbon vibrator, said card-holder comprising a deflector arranged to bend or deflect the card in the opposite direction as it is carried out of said pocket, whereby the card is restored to a flat condition.
32. In a typewriting machine, the combination with a platen, of a card-support for guiding cards into and out of the machine and across the printing line on a curve of radius sufficiently greater than that of the platen, whereby injurious bending of the card is avoided while the card is held firmly to the platen at the printing line, and means to automatically restore the card to a flat condition as it is removed from the machine.
33. In a typewriting machine, the combination with a platen, of a card-support for guiding cards into and out of the machine and across the printing line on a curve of radius sufficiently greater than that of the platen, whereby injurious bending of the card is avoided while the card is held firmly to the platen at the printing line, and a deflector positioned to engage the card and to deflect it in the opposite direction as it is advanced over the platen, whereby the initial curvature imparted to the card is counteracted so that the card is substantially flat as it leaves the machine.
34. In a typewriting machine, the combination with a roller platen, of means for supporting a card on a curve as it is being written upon, means coöoperating with the platen to advance the card thereover, and means to automatically straighten the card as it is advanced over the platen.
35. In a typewriting machine, the combination with a roller platen, of means for supporting a card in position to be written upon and by which the card is held on a curve to bear closely against the platen at the printing line, feed rolls arranged to bear against the card at the printing line and coöoperating with the platen to advance the card as the platen is rotated, and a deflecting plate positioned to deflect the upper portion of the card outwardly as the card is fed forward, and thereby straighten the card.
36. In a typewriting machine, the combination with a roller platen, of means for supporting a card in position to be written upon and by which the card is held on a curve to bear closely against the platen at the printing line, feed rolls arranged to bear against the card at the printing line and coöoperating with the platen to advance the card as the platen is rotated, a deflecting plate positioned to deflect the upper portion of the card outwardly as the card is fed forward, and thereby straighten the card, and means for shifting said rolls away from the platen to permit the card to be inserted freely into the card-supporting means.
37. In a typewriting machine, the combination with a roller platen, of card-holding means comprising a pocket located below the printing line to receive the lower edge of a card when the latter is in position to be written upon, feed rollers to bear against the platen at the printing line, supports on which said rollers are mounted, blades carried by said supports between the feed rollers and said pocket and forming with the latter a substantially continuous guide for the card from the feed rollers into said pocket, and means to shift said rollers toward and from the platen.
38. In a typewriting machine, the combination with a roller platen, of means for supporting a card on a curve to bear against the platen along the printing line, and a deflector plate extending lengthwise of the platen above the printing line with its lower edge close to the platen so that a card, as it is fed upwardly beyond the printing line, strikes said plate and is deflected outwardly sufficiently to straighten the card as it is removed in an upward direction from the machine.

LESTER A. WERNERY.
